UNITED STATES PATENT OFFICE.

OSCAR B. BJORGE, OF PORTLAND, OREGON, ASSIGNOR, BY MESNE ASSIGNMENTS, TO
CLYDE IRON WORKS, OF DULUTH, MINNESOTA, A CORPORATION OF MAINE.

LOGGING MECHANISM.

Application filed August 20, 1923. Serial No. 658,376.

To all whom it may concern:

Be it known that I, OSCAR B. BJORGE, a citizen of the United States, and a resident of Portland, county of Multnomah, and 5 State of Oregon, have invented a new and useful Improvement in Logging Mechanism, of which the following is a specification, the principle of the invention being herein explained and the best mode in which 10 I have contemplated applying that principle, so as to distinguish it from other inventions.

The present invention relates, as indicated, to logging mechanism and has more 15 particular reference to an improved mounting for the loading machinery as used in connection with the skidding machinery in general types of logging mechanisms. Such machinery is ordinarily mounted upon a 20 steel railway car or a sled, which may be readily moved to the place of operation, where a tower or spar tree is utilized to carry the various blocks for the skidding and loading lines. When the car is placed 25 adjacent the spar tree, the various cables are run upwardly to their respective blocks. Frequently the blocks for the skidding lines are mounted on one side of the tree and the blocks for the loading lines are mounted on 30 the opposite side. Consequently the various sets of lines leading from the two sides of the tree assume different angles as they are led to their respective winding drums, and it is to the correct mounting of said 35 drums, so that all the lines will lead properly thereto, that this invention is directed.

One of the objects hereof is to provide a simple and easily adjustable mounting for the loading machinery, whereby said machinery may be quickly angularly adjusted 40 with respect to the car and skidding machinery. The present invention also provides novel means for rigidly holding the loading machinery in adjusted position. To 45 the accomplishment of the foregoing and related ends, said invention, then, consists of the means hereinafter fully described and particularly pointed out in the claims.

The annexed drawings and the following 50 description set forth in detail certain mechanism embodying the invention, such disclosed means constituting, however, but

one of various mechanical forms in which the principle of the invention may be used.

In said annexed drawings:—

Fig. 1 is a side elevation of a logging mechanism in which my improved invention is incorporated;

Fig. 2 is a plan view thereof;

Fig. 3 is a plan view of the skidding 60 and loading machinery on an enlarged scale, showing the manner in which the various cables are led to a spar tree;

Fig. 4 is a side elevation of the loading machinery and its novel mounting; and

Fig. 5 is a front elevation on a still larger scale of the loading machinery, showing in detail the present improved mounting therefor, in connection with means for holding it in adjustable position.

The type of logging mechanism embodying the present invention is well known and only a general description thereof is deemed sufficient to give a complete understanding of the invention. 1 indicates a steel railway 75 car of the flat type mounted upon suitable wheels 2 which are adapted to convey the car over tracks 3. Mounted at one end of the car 1 is an engine 4 of usual construction, which is employed through suitable 80 valves or levers to control the operation of the skidding machinery which is designated generally at 5 and comprises a number of power driven winding drums 6 upon which are wound the skidding lines or cables 7. 85 In the present embodiment, the skidding machinery is mounted on the rear end of the car and in front of the skidding machinery is located the loading machinery 8, which also comprises a number of power driven 90 winding drums 9. Upon the drums 9 are wound the loading lines or cables 10. Other machinery such as a rigging engine 11, which is used for setting the lines and blocks, may also be mounted on the car 1. 95

In use, the car is moved over the track to the desired place of operation. Such place is usually selected adjacent a spar tree 12 which may be used as a tower for carrying the blocks of the various skidding and loading cables. The car is held in position very close to the tree and the lines from the logging mechanism are run upwardly to blocks mounted near the top

of the tree, from which blocks the lines are led to the scene of operation for skidding and loading of logs. In practice, the blocks 14 for the skidding lines are mounted on one side of the tree and the blocks 15 for the loading lines are frequently mounted on the other side thereof. It will be obvious that the various lines will assume different angles in leading from their respective blocks to the winding drums mounted on the car. In the case of the skidding lines, the flexibility in the mounting of the car itself, upon which is rigidly mounted the skidding machinery, compensates for the angularity of such lines and allows them to be wound on the skidding drums in proper lead.

It will also be obvious that it is necessary to provide means for tilting the winding drums of the loading machinery to one side or the other, so that the lines wound thereon will be in proper lead. Such tilting of the loading machinery must necessarily be independent of the mounting of the skidding machinery on account of the variance in the angularity of the skidding and loading lines. As illustrated in the drawings, the loading machinery 8 comprises a base or framework 16 upon which is mounted the loading drums 9 and the operating mechanism 17 therefor, which, in the present instance, comprises steam cylinders suitably connected with the drums. The framework is mounted slightly above the top of the car 1, so that it may be tilted from side to side. Such mounting comprises a longitudinal hinge or hinge members 18 which may be conveniently located along the central longitudinal axis of the loading machinery between the bottom of the framework and the top of the car. The hinge members 18 comprise a bracket 20 secured to the underside of the framework, a fulcrum pin 21 and a bracket 22 mounted upon the top of the car. As illustrated by the dotted axial lines in Fig. 5, the entire loading engine may be oscillated with respect to the car 1 about the pin 21 for the purpose of positioning the winding drums thereof in proper lead with the loading lines.

Means are provided for rigidly holding such loading engine in properly aligned position. Located at either side of the framework and passing through the top of the car 1 are suitable adjustable hold-down bolts 24. Adjusting nuts 25 are provided upon such bolts for the purpose of locking the framework 16 in adjusted position. In changing from one position to the other, it is only necessary to loosen the bolts and nuts on one side and tighten the bolts and nuts on the other side to place the engine in any desired position.

Other modes of applying the principle of my invention may be employed instead of

the one explained, change being made as regards the mechanism herein disclosed, provided the means stated by any of the following claims or the equivalent of such stated means be employed.

70

I therefore particularly point out and distinctly claim as my invention:—

1. In a logging mechanism, the combination with a platform, of a skidding engine rigidly mounted thereon, and a loading engine pivotally mounted on said platform, the winding drums of said skidding and loading engines being arranged transversely of the longitudinal axis of the platform, and said loading engine being pivoted along an axis parallel to said longitudinal axis.

2. In a logging mechanism, the combination with a platform, of a skidding engine mounted thereon, and a loading engine also mounted on said platform, the winding drums of said skidding and loading engines being arranged transversely of the longitudinal axis of the platform, said loading engine being pivotally mounted about a longitudinal fulcrum and being adapted to be angularly adjusted with respect to said skidding engine.

3. In a logging mechanism, the combination with a platform, of a skidding engine mounted thereon, and a loading engine mounted on a longitudinally extending hinge provided on said platform whereby said loading engine may be angularly adjusted with respect to said skidding engine, the winding drums of said skidding and loading engines being arranged transversely of the longitudinal axis of the platform.

4. In a logging mechanism, the combination with a platform, of a skidding engine mounted thereon, a loading engine mounted on a longitudinally extending hinge provided on said platform whereby said loading engine may be angularly adjusted with respect to said skidding engine, the winding drums of said skidding and loading engines being arranged transversely of the longitudinal axis of the platform, and means for holding said loading engine in adjusted position.

5. In combination, a railway car, a skidding engine rigidly mounted on said car, a loading engine spaced above the car, the winding drums of said skidding and loading engines being arranged transversely of the longitudinal axis of the platform, a longitudinal hinge member mounted centrally under and pivotally connecting said loading engine to said car, and adjustable bolts connecting each side of said engine to said car.

6. In a logging mechanism, the combination of a platform, a loading engine, co-operating pivot members on said platform and the base of said loading engine, respectively, and means for adjusting the base of said

loading engine to any degree of angularity to said platform.

7. In a logging mechanism, the combination of a platform, a loading engine, co-
operating pivot members on said platform
and the base of said loading engine, respec-
tively, and adjustable bolts connecting each

side of said engine to said platform to hold
the base of said engine at any desired angu-
lar adjustment about said pivot. ¹⁰

Signed by me this 11th day of August,
1923.

OSCAR B. BJORGE.
